HIGH VOLTAGE CONNECTOR

Donald R. De Tar, Stratford, Conn., assignor to Winchester Electronics, Incorporated, Norwalk, Conn., a corporation of Connecticut

Application January 30, 1956, Serial No. 562,115

6 Claims. (Cl. 339—94)

The present invention relates to an electrical connector and relates, more particularly, to an electrical connector for use at high voltages and high altitudes.

An object of the present invention is to provide an electrical connector which is capable of carrying high voltages at extremely high altitudes and in which the size and weight of the connector are kept at a minimum.

Another object of the invention is to provide an articulated high-voltage connector which will permit a small amount of relative movement between the plug and the receptacle, as will occur under conditions of severe vibration, without damage to the connector and without loss of voltage rating.

A further object of the invention is to provide a high-voltage connector in which the parts are of simple and inexpensive construction so that the connector may be made at low cost. In addition, the number and arrangement of the contacts used in the connector may be readily varied to meet various customer requirements.

Other objects and advantages of the invention will be apparent and best understood from the following description and the accompanying drawing in which:

Fig. 1 is a side view in vertical section of an assembled high voltage connector embodying the present invention shown on an enlarged scale;

Fig. 2 is a section view taken along the line 2—2 of Fig. 1;

Fig. 3 is a section view taken along the line 3—3 of Fig. 1;

Fig. 4 is a side view in vertical section of a part of the assembled connector shown in Fig. 1; and

Figs. 5 and 6 are graphical illustrations of the effect of changes in altitude on the breakdown voltage of an electrical connector and an air gap.

For use in air at an atmospheric pressure corresponding to sea level, satisfactory electrical connectors of small size may be provided for carrying electrical voltages up to several kilovolts as is commonly required for electronic equipment. Under such conditions, the voltage rating of such connectors may be increased by merely increasing the free air path between adjacent contacts in the connectors and the size of such connectors may be kept reasonably small by the use of telescoping barriers to provide a circuitous air path between the contacts.

However, with air under rarified conditions as at the extremely low pressure encountered in present high altitude flight, electrical conditions change radically and it becomes impractical to increase the voltage rating of a connector by merely increasing the free air path between the contacts. Thus, a serious problem is encountered in providing a satisfactory high-voltage connector which is small in size and light in weight for aircraft or similar uses. Such conditions are shown graphically in Figs. 5 and 6. In Fig. 5, the breakdown voltage in percent for an ordinary connector is plotted against altitude and from this it will be seen that the breakdown voltage at seventy thousand feet is only about 7% of the breakdown voltage at sea level. In other words, if the connector fails at

2

10,000 volts at sea level, it will fail at about 700 volts at seventy thousand feet. As will be seen from Fig. 6, this condition cannot be satisfactorily overcome by increasing the spacing between the contacts.

5 In Fig. 6, breakdown voltages have been plotted against air gap distances for altitudes of zero and seventy thousand feet. It will be seen that the slope of these curves decreases as the breakdown voltage is increased and this effect becomes much more pronounced at high altitudes.

10 Because of this, a high voltage connector for use at high altitudes with free air paths between the contacts would be extremely large and heavy and therefore unsuited for most aircraft or similar applications as a large number of connectors are generally required for such installations and their size and weight becomes an important factor.

In accordance with the present invention, it has been found that a satisfactory high voltage electrical connector which will occupy a reasonably small space and be light in weight may be provided for such use by interrupting the air path between the contacts with a solid dielectric material at one or more points. The construction of one form of connector embodying these principles is shown and described hereinafter.

25 Referring to Fig. 1, there is an assembled connector which comprises a receptacle 10 and a plug 11. The receptacle and the plug each include a body portion 12 which may be molded from any suitable insulating material such as melamine resin. The molded body portions for the plug and the receptacle are cylindrical in shape but may be formed in any desired shape. The body portions may also be identical for economy in manufacture.

30 Each of the body portions has spaced bores 13 and 14 extending therethrough. Male contact members 15 are mounted in the bores in the plug body and female contact members 16 are mounted in the receptacle body. Portions of the contact members are exposed at the mating faces of the respective body portions so that when the plug and receptacle are brought into assembled relation, as shown in Fig. 1, the exposed ends of the male contacts will engage with the exposed ends of the female contacts and make an electrical connection therewith. The other ends of the contacts also extend beyond the outer ends of the plug and receptacle bodies and are provided with the usual wiring terminals. The contacts are 35 of conventional construction and may be held in place by C-rings 17 in the usual manner.

40 The mating faces of the body portions have enlarged openings 18 and 19 communicating, respectively, with the bores 13 and 14. Intermediate insulating members 50 20 of spool-like shape which may be made of nylon or other suitable material extend into the enlarged openings in the plug and receptacle bodies and surround the male and female contacts at their juncture points when the 55 plug and receptacle are assembled. The spool-like members each have a bore extending therethrough and may be loosely attached to one of the contact members as by engagement of a shoulder 21 on the female contact with a shoulder 22 in the bore of the insulating member.

60 The intermediate insulating members have annular grooves 23 in their outer surfaces in which resilient rubber O-rings 24 surrounding the members are retained. The resilient rings 24 are under compression between the sides of the enlarged openings in the mating faces of the 65 plug and receptacle and effect an air-tight seal between the body portions and the intermediate insulating members which interrupts the free air path that would otherwise exist between the exposed portions of adjacent contact members or other points to which there might be leakage.

70 In this arrangement, the intermediate insulating members have a limited movement or float which compensates

for slight misalignment of the two connector halves, and which also insures maintenance of an air-tight seal under conditions causing small relative motion between the plug and the receptacle.

The outer ends of the plug and receptacle body portions are provided with round bosses 25 through which the bores 13 and 14 extend. After a connection has been made to the terminal of a contact, one end of a rubber sleeve 26 is stretched over the boss through which the contact extends and the other end of the rubber sleeve is placed over the jacket of the cable 27 which is attached to the terminal of the contact. The exposed terminal connection to the contact is thus enclosed in an air-tight manner which interrupts the air path between the terminal ends of adjacent contacts or other leakage points.

It will be understood that various changes and modifications may be made in the embodiment of the invention illustrated and described herein without departing from the scope of the invention as defined by the following claims.

I claim:

1. A miniature type electrical connector for use at high voltages and at high altitudes which comprises a pair of bodies of insulating material forming a plug and a receptacle, said connector bodies having mating faces with opposing spaced recesses formed in said mating faces, spaced contact members carried by each of the connector bodies, said contact members having exposed contact portions located in the spaced recesses in the connector bodies, the contact portions of the contact members carried by one of the connector bodies entering into engagement with the contact portions of the opposing contact members carried by the other connector body, a separate member of insulating material surrounding the interengaged portions of each set of contact members and extending into the opposing recesses in the mating faces of the connector bodies, and means for forming an air-tight seal between said separate members and each of the connector bodies, said sealing means comprising members of resilient insulating material located between and engaging with the sides of the recesses in each of the connector bodies and the separate insulating members.

2. In a miniature type electrical connector for use at high voltages and at high altitudes, the combination which comprises a pair of connector bodies of insulating material forming a plug and a receptacle, said connector bodies having mating faces with opposed spaced recesses formed therein, a plurality of spaced contacts carried by each of the connector bodies, each of said contacts having an exposed portion located in one of the spaced recesses in the respective connector bodies with the exposed portions of the contacts carried by one of the connector bodies entering into engagement with the exposed portions of the contacts carried by the other connector body when the mating faces of the connector bodies are brought into engagement with each other, a separate member of insulating material surrounding the interengaged portions of each set of contacts and extending into the opposing recesses in the mating faces of the connector bodies, and resilient sealing means engaging with said separate members and surfaces of the connector bodies defining the re-

cesses in the mating faces thereof and forming an air-tight seal therebetween whereby air-paths between exposed portions of the spaced contacts are interrupted.

3. In a miniature type electrical connector as defined in claim 2 wherein the resilient sealing means includes a ring of resilient material extending around each end of the separate insulating members.

4. A miniature type electrical connector for use at high voltages and at high altitudes which comprises a connector body formed from a relatively rigid insulating material, said body having a plurality of spaced recesses in one face thereof, a plurality of contacts extending through said body in spaced relation to each other, each of said contacts having an exposed portion projecting into one of the recesses, a separate member formed from a relatively rigid insulating material surrounding the exposed portion of each of the contacts and extending into the recess in which said exposed portion is located and a resilient member located between each of the separate insulating

members and surfaces of the connector body defining the recesses into which said insulating members extend, said resilient members being under compression and forming air-tight seals between the separate insulating members and the connector body whereby the air-path along the face of the connector body between the exposed portions of the contacts is interrupted.

5. A miniature type electrical connector as defined in claim 4 wherein the separate members of insulating material project beyond the face of the connector body containing the recesses.

6. A miniature type electrical connector for use at high voltages and at high altitudes which comprises a connector body formed from a relatively rigid insulating material, said body having a plurality of spaced recesses in one face thereof, a plurality of contacts extending through said body in spaced relation to each other, each of said contacts having an exposed portion projecting into one of the recesses, a separate member formed from a relatively rigid insulating material surrounding the exposed portion of each of the contacts and extending into the recesses in which said exposed portion is located and a sealing ring of resilient material interposed between each of the separate members and the surfaces of the connector body forming the sides of said recesses, said rings being under compression and forming air-tight seals between the separate insulating members and the connector body whereby the air-path along the face of the connector body between the exposed portions of the contacts is interrupted.
